UNITED STATES PATENT OFFICE.

GUY B. HUMES, OF CHICAGO, ILLINOIS.

ATTACHMENT FOR REED MUSICAL INSTRUMENTS.

1,384,564.

Specification of Letters Patent. Patented July 12, 1921.

Application filed June 30, 1919. Serial No. 307,634.

To all whom it may concern:

Be it known that I, GUY B. HUMES, a citizen of the United States, and a resident of the city of Chicago, county of Cook, and 5 State of Illinois, have invented a certain new and useful Attachment for Reed Musical Instruments, of which the following is a specification.

My invention relates to an attachment for 10 reed musical instruments and has for its object the provision of a device which, when used with reed musical instruments, will produce a discordant and inharmonious sound, if desired, while the instrument is 15 being played in the usual manner. Other objects will appear hereinafter.

Figure 1 is a fragmentary side elevational view of a saxophone embodying the invention, with parts in section.

20 Fig. 2 is a transverse sectional view taken on substantially the line 2—2 of Fig. 1.

Fig. 3 is a fragmentary side view of a saxophone embodying the invention.

25 Fig. 4 is a transverse sectional view taken on substantially line 4—4 of Fig. 1.

Fig. 5 is a plan view of my invention.

Fig. 6 is a plan view of a key opening device.

30 Fig. 7 is a side elevational view of the device shown in Fig. 6.

In the drawings I have represented my device applied to a saxophone, but I wish it understood that this device may be applied to any reed musical instrument. As shown, 35 the saxophone 8 is provided with the usual lever 9, which is pivotally connected to the tubular portion of the saxophone, as at 10, and has the usual finger piece 9^a. Secured to one end of the lever 9 is a suitable cap 11, 40 which is used to close the orifice in the tubular portion of the musical instrument, as will be readily understood. The usual stop- 45 post 12 is shown which prevents the outer end of the lever 9 from being moved inwardly too great a distance. Provided upon the tubular portion of the musical instrument, adjacent the orifice on which the cap 11 seats, is the usual bifurcated guide-post 13, the lever 9 being adapted to engage be- 50 tween the bifurcated portions of this guide- post 13.

My device which I attach to reed musical instruments, consists of a tubular member 16, which is adapted to be inserted in an 55 orifice of the musical instrument and forms a support for a membrane and co-operating

parts as hereinafter described. This tubular member is cut obliquely at the end which is to be thrust into the interior of the musical instrument, diagonally, the longer end 60 of this tubular member 16 facing toward the mouth of the musical instrument. From this construction it is readily apparent that the obliquely cut edge of the tubular member 16 inclines away from the mouth of the 65 instrument and toward the inner wall thereof. The air strikes the member 16 in its downward passage and it is forced in an outward direction through the tubular member 16. Secured on the tubular member 16, 70 by solder or other suitable means, is a disk-like member 14, having a flange 15, forming a cup-shaped disk. The member 14 is provided at its center with an opening substantially the same size as the opening in the 75 tubular member 16. The cup-shaped disk is mounted upon the tubular member 16 so that the opening in the portion 15 registers with the opening in the tubular member 16. The tubular member 16 is made of a less diameter than the orifice in the musical instrument in which it is to be inserted, and surrounding the tubular member 16, adjacent the inner face of the member 15, is a collar 17 80 of cork, rubber or other yielding material. This cork or rubber forms a sort of packing 85 for the member 16 and prevents the passage of air out of the musical instrument around the exterior of the member 16, as will be readily understood. Mounted within the cup-shaped disk so as to lie upon the inner surface of the member 14, is a membranous 90 film 18, formed of fish skin, oil paper, silk or the like. A ring 19 is adapted to be secured in the cup-shaped disk over said membrane, 95 this member 19 snugly engaging the inner surface of the flange 15.

As clearly shown in Fig. 2, the member 14 is of a larger diameter than the usual flange which surrounds the orifice leading 100 into the interior of the musical instrument. It is evident that, upon securing the member 19 in the cup-shaped disk, the membranous film 18 will be securely locked in position.

In the use of this device, although it may 105 be applied to any of the keys with equal success, I prefer to apply it to one of the higher, and therefore rarely used, keys. When the device is applied to a musical instrument as I have described, the cap 11 seats upon 110 the outer edge of the device and thereby closes the orifice leading into the musical in-

strument in a similar manner as the orifice is closed when the device is not applied thereto. Inasmuch as the key to which the device is ordinarily applied, is rarely used, 5 it is evident that the instrument may be used in its usual manner. When it is desired to produce the "jazz" effect which my invention will produce, it is necessary simply to raise the cap 11 out of engagement with the cup- 10 shaped disk.

In order to continue to sound the "jazz" note it is necessary to retain the cap 11 in this raised position. Inasmuch as this cannot conveniently be done by the one playing 15 the instrument, I have provided a device which maintains the cap in its elevated position.

I have provided a member which consists of an annular portion 20, projecting laterally from one edge of which is a portion 21, having one edge thereof beveled or inclined as shown in Fig. 7. Projecting tangentially from one side of the member 20 is a suitable handle 22. In assembling my invention upon a musical instrument of this class, the lever 9 bearing the cap 11 is dismounted from its pivotal connection at 10, and the member 20 is slid over the guide-post 13 embracing both bifurcated sections 25 thereof, the member 21 projecting outwardly from the musical instrument. The cap raising device is so constructed that, when the lever 9 rests upon the portion 21', the cap 11 will tightly close the orifice leading into the 30 instrument. Upon rotating the member upon the guide-post 13 by means of pressing against the handle 22, the inclined edge of the member 21 is brought into engagement with the lever 9, thereby raising the same. 35 The device is so constructed that the lever 9 may rest upon the portion 21, and thereby the cap 11 would be retained in elevated position.

When this device is used upon a reed musical instrument and the stop-cap 11 is raised therefrom, upon the playing of the instrument in the usual manner the tones thereof are accompanied by a harsh or grating sound, or what is now popularly termed a 50 "jazz" sound, caused by the vibration of the membranous film.

By use of my device a single instrument may be caused to produce a "jazz" effect, which formerly could be obtained only by 55 playing two or more instruments at the same time. The operation of the device produces a greater volume of sound than is produced by the instrument when played without the attachment. More than one of such 60 devices may be used on an instrument, if desired, to further increase the volume of sound and intensify the discordant "jazz" note.

While I have illustrated and described the 65 preferred form of construction for carrying

my invention into effect, this is capable of variation and modification without departing from the spirit of the invention. I, therefore, do not wish to be limited to the precise details of the construction set forth, 70 but desire to avail myself of such variations and modifications as come within the scope of the appended claims.

Having described my invention, what I claim as new and desire to secure by Letters 75 Patent, is:—

1. A tone modifying attachment for a key opening of a musical instrument; a support in said opening and communicating therewith; a membrane on said support; and means for retaining said membrane in position, substantially as described. 80

2. A tone modifying attachment for a key opening of a reed musical instrument; a tubular support in said opening and communicating therewith; a membrane on said support; and means for holding said membrane in position, substantially as described. 85

3. A tone modifying attachment for a key opening of a reed musical instrument; a tubular support in said key opening and communicating therewith; a disk on said tubular member; an opening in said disk communicating with said tubular member; a membrane over said opening; and a ring for holding said membrane in position, substantially as described. 90

4. A tone modifying attachment for a key opening of a reed musical instrument; a tubular support extending through said opening having its inner end obliquely cut, a flanged disk on the outer end of said tubular member; an opening in said flanged disk communicating with said tubular member; a membrane covering said opening; a cork ring engaging the inner walls of the flange on said disk for holding said membrane in position, substantially as described. 100

5. A tone modifying attachment for a key opening of a reed musical instrument; a support having a tubular member inserted in said key opening, said tubular member being obliquely cut on its inner end, the longer end of said tubular member facing the mouth of the instrument; a flanged cup-shaped disk on the outer end of said tubular member and integral therewith; an opening in said flanged cup-shaped disk communicating with said tubular member; a fish skin membrane over said opening; and a cork ring engaging the inner wall of said cup-shaped disk to hold said membrane in position, substantially as described. 110

6. A tone modifying attachment inserted between the key and key opening of a reed musical instrument; a tubular member in said opening; a flanged disk at the outer end of said tubular member and integral therewith; an opening in said flanged disk; a membrane over said opening; and a cork 120

115

120

125

130

ring engaging the inner walls of said flanged disk and holding said membrane in position, said attachment being operated by moving the key into and out of engagement with the flanged disk, substantially as described.

7. A tone modifying attachment inserted between the key and key opening of a reed musical instrument, a tubular member in said opening; a flanged disk at the outer end 10 of said tubular member and integral therewith; an opening in said flanged disk; a membrane over said opening; a cork ring engaging the inner walls of said flanged disk and holding said membrane in position, 15 said attachment being operated by moving the key into and out of engagement with the flanged disk; and a stop member on said instrument adjacent said disk for holding said key out of engagement with said disk, substantially as described.

8. A tone modifying attachment inserted 20 between the key and key opening of a reed musical instrument; a tubular member in

said opening; a flanged disk at the outer end 25 of said tubular member and integral therewith; an opening in said flanged disk; a membrane over said opening; a cork ring engaging the inner walls of said flanged disk and holding said membrane in position, said attachment being operated by moving the 30 key into and out of engagement with the flanged disk; a stop on said instrument rotatably mounted adjacent said disk; a projection on said stop; and a handle for moving said projection into and out of engagement 35 with the under side of said key to hold said key disengaged from said flanged disk, substantially as described.

In testimony whereof I have signed my name to this specification in the presence of 40 two subscribing witnesses.

GUY B. HUMES.
